UNITED STATES PATENT OFFICE

SELWYN R. BLACKSTONE, OF MILWAUKEE, WISCONSIN, ASSIGNOR, BY MESNE ASSIGNMENTS, TO BLACKSTONE INVENTIONS, INC.

BOTTLE CAPPER

Application filed February 14, 1929. Serial No. 339,907.

This invention relates to bottle cappers.

An object of the present invention is to provide an efficient bottle capping device of simple design and sturdy construction to withstand long and hard usage.

Another object of the present invention is to provide a bottle capper which can be manufactured at an extremely low cost.

While numerous bottle capping devices are now on the market none of them satisfactorily fulfill all the requirements of a ready capping device for the reason that they are either heavy and bulky or that they require adjustment to adapt them for bottles of different capacities. The present invention provides a bottle capper in which the above noted objections have been eliminated which is extremely simple in form, and which can with facility be used on bottles of different capacities without requiring adjustment.

A further object of the present invention is the provision of means on the body portion of the capper to retain the bottle against movement and to distribute the capping pressure about the periphery of the bottle neck to thereby avoid bottle breakage during the capping operation.

Other objects and advantages will appear from the following description of two illustrative embodiments of the present invention.

In the drawings:

Figure 1 represents a vertical longitudinal midsection taken through the bottle capper.

Fig. 2 represents an end elevation of the capper shown in Figure 1.

Fig. 3 represents a top plan view of the same capper.

Fig. 4 is an elevational view showing a modified form of the device.

In the embodiment of the invention shown in Figures 1, 2 and 3 of the accompanying drawings, the bottle capper comprises a piece of sheet metal bent intermediate its ends to form a saddle 10 having upwardly extending converging arms 11 and 12. A handle 13 is pivotally mounted between the arms 11 and 12 on a rivet 14. A capping die 15 of usual form is permanently secured to a U-shaped strap 16 which in turn is pivotally mounted on the handle 13 by means of a rivet 17. It

will be noted from the drawings that the rivet 17 lies closely adjacent the handle fulcrum rivet 14 so as to provide a high mechanical advantage by which a heavy capping thrust may be applied by the exertion of a comparatively light pressure upon the outer end of the handle 13.

The body portion of the saddle 10 is so designed as to form a bottle neck receiver which will sustain the capping thrust and retain the bottle against movement during the capping operation. The arms 11 and 12 merge into the body portion to form an apron 18, which envelopes a portion of the bottle neck and is of sufficient depths to contact with the side 19 of the bottle 20 well below the lobe or bead 21 on the bottle. The top of the apron 18 is preferably provided with an inwardly directed flange 22 having an arcuate edge 23 designed to snugly engage the neck

25 of the bottle immediately below the bead 21. The extremities of the flange 22 are bent slightly upwardly to form tangs 24 adapted to react against the face of the bead to retain the neck of the bottle in firm contact with the edge 23 of the flange throughout the arcuate portion thereof. By this peripheral contact between the edge of the flange and the bottle neck, the pressure reacting from the capping thrust is distributed around the bottle neck to thereby avoid bottle breakage

70 that might otherwise occur if the flange were in contact with the bottle at two diametrically disposed points only. The bottle cap 26, of standard form, is shown in section on the bottle and within the capping die 15. (See Fig. 1.)

It will thus be noted that the flange 22 forms a seat for the bottle neck, well adapted to sustain the capping thrust, and that the depending apron 18 reacts against the side of the bottle to thereby retain the same against rocking in the seat and thus sustain the reaction of the saddle 10 imposed by the thrust inducing action of the handle 13 thereon. In fact the seat forming flange 22 and apron 18 coact with the bottle in such manner that the bottle becomes in effect an integral

80 part of the saddle, the body of the bottle ac-

virtually functioning as a lever during the capping operation.

It will be noted that the upwardly extending, converging arms 11 and 12 of the saddle 10 terminate at a point near the axis of the bottle and above the bottle. The positioning of the rivet 14, which forms a fulcrum for the handle 13, adjacent the extremity of the arms serves a two-fold purpose. It facilitates the accomplishment of obtaining greater mechanical advantage upon the manipulation of the handle, as previously described, and also functions to transmit the pressure applied to the handle 13 to the saddle 10 in such a manner as to apply in effect a vertical pressure on the flange 22 to resist and sustain the pressure exerted by the capping die and in addition tends to increase the gripping action of edge 23 against the neck of the bottle, by virtue of the convergence of the arms 11 and 12.

The operation of capping a bottle by means of the present capper is extremely simple. The bottle 20 is slipped into the saddle 10 through the open side thereof so that the flange 22 engages the neck 25 of the bottle immediately below the bead 21; with the tangs 24 bearing against the side of the bead. The handle 13 may then be raised to a position approximating the dotted line showing in Fig. 1 and the bottle cap 26 placed in its proper position. The handle 13 may then be swung downwardly until the capping die 15, the cap 26, and the mouth of the bottle are in proper alignment. At this time the bottle may be grasped firmly in one hand and the handle 13 grasped by the other hand. By exerting pressure on the handle 13 the capping die 15 forces the cap 26 over the mouth of the bottle and crimps the fluted periphery of the cap to engage the cap firmly on the mouth of the bottle to seal the same. After the cap has been driven home on the bottle the capper is released by raising the handle 13 to free the capping die 15 from the cap after which the saddle is removed from the bottle.

It will be noted that the simplicity of operation of this device along with the simplicity of the device itself is such as to make the capping of a bottle by use of this device virtually as simple as the present methods used for decapping bottles.

The modified form of the device shown in Fig. 4 is similar in many respects to the embodiment shown in Figures 1, 2 and 3. It comprises a saddle 10' having upwardly extending converging arms 12' and a pivot pin 14' adjacent their upper extremity. A capping die 15' carried by a U-shaped strap 16' is pivotally mounted on a bracket 27 by means of a pin 17' which lies closely adjacent the pivot pin 14'. The bracket 27 is carried by an integral base plate 28 which may be

anchored to a wall 29 or similar surface by means of screws 30.

The operation of capping a bottle by use of this modified form differs slightly from that previously described in so far as the bottle itself forms the lever arm, by which pressure is exerted to cap the bottle. The method of capping a bottle with this form of capper is extremely simple however. The saddle 10' is preferably raised to a position approximating that shown in the dotted lines of Fig. 4, and the bottle 20' slipped into the saddle with the flange 22' engaging the neck 25' immediately below the bead 21' of the bottle. A cap 26' may be readily tapped in position on top of the bottle before applying the bottle to the capper. The capping die 15' is then raised to a point where it will engage the cap 26' as the bottle is swung downwardly toward the full line position shown in this figure. When the capping die has engaged the cap on the bottle the bottle is forced downwardly to drive the capping die and cap over the mouth of the bottle to firmly seal the same in the manner previously described. It will readily be seen that the saddle 10' and bottle 20' rock as a unit about the pivot pin 14'. It will also be noted that the pivot pin 17' upon which the capping die 15' is mounted lies below and a short distance from the pivot pin 14'. Obviously, when the saddle and bottle are rocked from the dotted line position (see Fig. 4) to the full line position, the distance between the capping die and the top of the saddle will be materially decreased and by reason of this fact the cap will be forced over the head of the bottle and crimped in position to seal the bottle.

One of the outstanding features of the present invention lies in the fact that the bottle capper is so designed as to permit use on any of a plurality of bottles having different capacities without the necessity of adjustment of the capper. This condition is due to the fact that all bottles of this type have a standard neck dimension, and I predicate a large portion of my success in this endeavor to the formation of a saddle to receive and retain the bottle in proper position to be acted upon by a capping die to provide a successful, simple and efficient bottle capper.

Various changes may be made in the embodiments of the invention hereinabove specifically described without departing from the invention as defined in the appended claims.

I claim:

1. A bottle capper comprising two pivotally connected members, a capping die on one of said members, an arcuate flange on the other of said members for embracing the neck of a bottle to support the same against the thrust of said capping die, and tangs on said flange coacting with said bottle to insure pe-

ipheral contact between said flange and bottle.

2. A bottle capper comprising a stationary support, a bottle capping die pivotally mounted on said support, and a bottle neck seat pivotally mounted on said support and coacting with said die to force a cap onto the neck of the bottle.

3. A bottle capper comprising two pivotally connected members, a capping die operatively connected with one of said members, the other of said members having an arcuate seat open at one side to freely admit a bottle neck and to sustain the same against the thrust of said capping die, that portion of said seat adjacent said open side being upwardly curved to retain said neck in peripheral contact with said seat.

4. In a bottle capper the combination of a capping die, a bottle neck receiver, a member coacting with said die and receiver to induce a capping thrust, a bottle neck seat on said receiver for sustaining said capping thrust, and bottle engaging means on said receiver through which the bottle sustains the reaction of said receiver resulting from the thrust inducing action between said receiver and member.

5. In a bottle capper the combination of a capping die, a bottle neck receiver, a member co-acting with said die and receiver to induce a capping thrust, a bottle neck seat on said receiver for sustaining said capping thrust, said seat being open at one side to freely admit the bottle neck, and a bottle engaging member disposed below the other side of said seat for transmitting to the bottle the reaction of said receiver resulting from the thrust inducing action between said receiver and member.

6. In a bottle capper the combination of a capping die, a bottle neck receiver, a member coacting with said die and receiver to induce a capping thrust, the action between said member and receiver tending to induce a rocking action between said receiver and a bottle therein, and bottle engaging means on said receiver for effectively preventing such rocking action whereby the bottle is instrumental in effecting the thrust inducing action between said receiver and member.

7. In a bottle capper the combination of a bottle receiver having an open sided seat for receiving a bottle neck, upwardly convergent supporting arms for said receiver, a capping die, and a member pivotally connected with said arms and with said die for inducing a capping thrust between said die and seat, said convergent arms and member being so arranged as to induce a closing pressure of said seat against the bottle neck during the capping operation.

8. In a bottle capper the combination of a bottle neck receiver, comprising a piece of sheet metal bent intermediate its ends to

form a saddle for embracing the bottle neck, an inturned flange at the top of said saddle forming a bottle neck seat, the bottom of said saddle being arranged for contact with the bottle, a pair of spaced arms extending upwardly from said saddle, a capping die, and a member rockably connected with said arms and die for effecting a capping pressure.

9. A device of the character described comprising a capping member and a support therefor in combination with a bottle engaging member comprising integrally a sheet metal strip bent upon itself to provide a bottle engaging bight and having in said bight a semi-circular inwardly turned marginal flange on its upper margin, the portions of said strip beyond said bight being upwardly turned in spaced relation sufficient to permit the free passage of a bottle mouth to a position such that the neck of such a bottle may be engaged by the flange in said bight, the upper portions of said strip being pivoted to said support.

10. In a device of the character described, the combination with a capping member and a support therefor, of a bottle engaging bight into which the neck of a bottle is laterally receivable, an arm projecting upwardly from said bight at each side of the path of a bottle introduced therein, and a pivotal connection between said support and said arms, the length of said arms and said capping member being such with respect to a bottle and cap therefor, that in the engagement of a cap by said capping member a line drawn between said pivotal connection and the point of application of pressure on said capping member will be at an acute angle with respect to the direction of movement of said capping member toward said bottle, and said bight opening toward said pivotal connection, whereby a component of the reaction of thrust of said support upon said bottle engaging member will tend to draw said bight snugly to the neck of a bottle engaged therein.

In witness whereof, I hereunto subscribe my name this 12th day of February, 1929.
